ALEXANDER STEVENSON, OF NEW YORK, N. Y.

Letters Patent No. 97,824, dated December 14, 1869.

IMPROVEMENT IN CARPET-BEATER AND CLEANER.

The Schedule referred to in these Letters Patent and making part of the same.

To all whom it may concern:

Be it known that I, ALEXANDER STEVENSON, of New York, in the county of New York, and State of New York, have invented a new and improved Carpet-Cleaner; and I do hereby declare that the following is a full, clear, and exact description thereof, which will enable others skilled in the art to make and use the same, reference being had to the accompanying drawings, forming part of this specification.

This invention relates to new and useful improvements in carpet-cleaning devices, having for its object to provide a simple and efficient apparatus, consisting of a yielding bed, brushing-rollers, moving-rollers, and a beating-apparatus, whereby the carpet, being wound upon a roller or rollers, may be moved along, from time to time, over the said yielding bed and brushing-rollers, and be beaten and brushed, all as hereinafter more fully specified.

Figure 1 represents a sectional elevation of the said yielding bed, brushing and carrying-rollers, and

Figure 2 represents a plan view of the beating-instrument.

Similar letters of reference indicate corresponding parts.

On any suitable frame, A, I arrange a yielding bed, B, consisting of cords or straps, stretched over coiled furniture-springs, C, from side to side of the frame.

The cords are, preferably, made of hair, as more durable, and better adapted for drawing the carpet over them.

Below the ledges of the bed, on each side, I place brushing-rollers D, and below these, winding-rollers E, all having hand-crank.

The carpet to be cleaned is first-rolled upon one of the winding-rollers E, except a small portion at one end.

This is laid across the bed B, and beaten with a beating-instrument, F, represented in fig. 2.

The said part, after being sufficiently beaten, is then passed along to the opposite roller E, and engaged thereon, and winding off the other. The carpet is, from time to time, wholly passed over the said bed, to be beaten.

The beating-instrument consists of a pair of handles, G, to which are connected two bent metal straps, H, for the support of a series of parallel wires, I, arranged at equal distances apart, and connected at the outer ends to a tie-bar, K. This instrument acts upon a large area of surface at one blow, and is very effective; and, together with the yielding bed B, furnishes an exceedingly efficient carpet-cleaning apparatus.

If desired, aprons of woven fabric may be suspended over the winding-rollers, to prevent the dirt, passing away from the part being beaten and the brushing-rollers, from again settling on the cleaned part.

Having thus described my invention, I claim as new, and desire to secure by Letters Patent—

1. The combination of a yielding bed, B, brushing-rollers D, and winding-rollers E, substantially as specified.

2. The arrangement of the yielding beating-bed, with the device for rolling D D and E E, as shown and described, in combination with the beater K F I I H G G, for the purpose specified.

The above specification of my invention signed by me, this 21st day of April, 1869.

ALEX. STEVENSON.
